ENGINE STARTER

John W. Fitz Gerald, deceased, late of Milwaukee, Wis., by Mary C. Fitz Gerald, executrix, Milwaukee, Wis., assignor to Briggs & Stratton Corporation, Milwaukee, Wis., a corporation of Delaware

Application June 19, 1943, Serial No. 491,514

4 Claims. (Cl. 74—7)

This invention relates to engine starters of the so called automatic type wherein the pinion is automatically propelled to and from mesh with the ring gear of an engine to be started.

A copending application Serial No. 491,513, filed June 19, 1943, describes the advantages of using a stack of cupped spring washers as the resilient driving connection through which torque is transmitted to the pinion of the starter.

The present invention employs the same type of resilient driving connection but has as its object to so utilize the same that the application of the cranking load is cushioned solely by slippage in the driving connection. As a result the cushioning of the starting load is more easily controlled and predetermined as only one factor namely slippage in the driving connection per se must be taken into account.

However, endwise resiliency is still retained to accommodate misalignment of the pinion and ring gear during the meshing operation.

It is, therefore, a specific object of this invention to provide an engine starter wherein the resilient driving connection through which torque is transmitted to the pinion consists of a slipping disc coupling or clutch having endwise resiliency inherent therein.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate two complete examples of the physical embodiment of the invention constructed in accordance with the best modes so far devised for the practical application of the principles thereof, and in which:

Figure 1 is a view in side elevation with parts thereof in section of an engine starter embodying this invention, said view showing the pinion in its normal retracted position;

Figure 2 is a view similar to Figure 1 but showing the parts in the positions they assume in the event of improper meshing, that is, end-to-end abutment of the pinion and ring gear teeth;

Figure 3 is a view similar to Figure 1 showing the pinion fully meshed;

Figure 4 is a perspective view of a part of the pinion hub and illustrating the manner in which the pinion stop in that form of the invention shown in Figures 1, 2 and 3 is constructed; and

Figure 5 is a view similar to Figure 1 illustrating the application of this invention to a starter embodying the conventional type of pinion stop.

Referring now more particularly to the accompanying drawings, in which like numerals indicate like parts, the numeral 5 designates the shaft of a starter motor upon which the starter indicated generally by the numeral 6 is mounted. The starter comprises a pinion 7 movable along the shaft into and out of mesh with the ring gear 8 of an engine to be started and means for actuating and driving the pinion.

The pinion 7 has a hub 9 internally threaded as at 10 to receive the threaded portion 11 of an actuator 12. The actuator 12 consists of a tube the outer portion of which has the external threads 11 and the inner portion of which has a smooth cylindrical surface 13 of a diameter substantially equal to or at least not greater than the root diameter of its threaded portion 11. It is freely slidable and rotatable on the motor shaft and is drivingly connected with the shaft through an impulsive endwise resilient driving connection 14.

25 This driving connection comprises a flange 15 on the actuator, a drive head 16 fixed to the motor shaft, and a stack of alternately arranged cupped spring washers 17 confined between the flange 15 and the drive head. A shell 18 attached 30 to the flange 15 and engaged over a flange on the drive head holds these parts against separation and maintains the stack of spring washers under a degree of compression.

By virtue of the endwise pressure on the stack 35 of cupped spring washers they engage at their inner and outer peripheral portions with sufficient friction to provide for the initial transmission of torque from the drive shaft to the actuator to propel the pinion to its operative driving position shown in Figure 3 and defined by a pinion stop indicated generally by the numeral 19.

The pinion stop 19 contrary to customary practice is between the hub of the pinion and the actuator so that in picking up the cranking load 45 there is no increase of the endwise pressure on the stack of cupped spring washers. Consequently, the cushioning of the application of the cranking load to the starter is obtained solely by the frictionally resisted slippage between the spring washers of the driving connection.

However, in the event of tooth abutment as shown in Figure 2 the endwise resiliency of the stack of spring washers provides the desired cushion and accommodates such misalignment.

The pinion stop 19 is of novel and simple con-

struction. It consists of a slab 20 off the end of the pinion hub secured back on the hub but in a position revolved several degrees from its original position so that the teeth thereof are misaligned with the teeth of the hub. In this manner the teeth of the slab form abutments across the ends of the spaces of the hub to collide with the ends of the teeth 11 on the actuator.

To hold the slab 20 in this position its outer peripheral portion is notched to provide lugs 21 and spaces 22 and the end of the pinion hub is similarly notched to provide complementary lugs 21' and spaces 22'; and a spring ring 23 snapped into a groove 24 on the lugs 21' of the pinion hub holds the slab assembled with the hub.

It is, of course, also possible to use the conventional form of pinion stop collar as shown in Figure 5. Here the actuator has a smooth surfaced extension 25 projecting through the pinion and the stop collar 26 is secured on the outer end thereof in a position to be engaged by the pinion when fully meshed with the ring gear.

From the foregoing description taken in connection with the accompanying drawings, it will be readily apparent to those skilled in the art that this invention provides a novel manner of obtaining torsional and endwise cushioning and that because only one factor, namely, slippage between the cupped washers and the driving connection is utilized in cushioning the application of the cranking load on the starter, it is possible to more accurately control the cushioning effect.

What is claimed as the invention is:

1. In an engine starter: a pinion having an internally threaded hub portion; a pinion actuator having a hub the outer end portion of which is externally threaded and threadedly engaged in the hub of the pinion and the inner portion of which is smooth surfaced and of a diameter no greater than the root diameter of its threaded outer end portion; and a pinion stop for limiting endwise movement of the pinion outwardly of the actuator comprising a collar having internal threads similar to those of the pinion hub and fixed to the end of said pinion hub in a position angularly offset with respect to the threads thereof to provide abutments across the ends of the spaces of the internal threads of the pinion hub portion to collide with the adjacent ends of the threads on the actuator.

2. In an engine starter: a pinion having an internally threaded hub portion; a pinion actuator having a hub the outer end portion of which is externally threaded and threadedly engaged in the hub of the pinion and an inner portion of which is smooth surfaced and of a diameter no greater than the root diameter of its threaded outer end portion; and a pinion stop for limiting endwise movement of the pinion outwardly of the actuator comprising a relatively short length of the internally threaded pinion hub having its outer periphery notched to provide lugs and spaces therebetween, the end portion of the pinion hub remote from the pinion being similarly notched to provide complementary lugs and

spaces therebetween; and means for securing the short length of internally threaded pinion hub to said end portion of the pinion hub with its lugs in the notches of the pinion hub and with the threads of said short length of pinion hub disaligned with the threads of the pinion hub portion so as to provide abutments engageable with the ends of the threads on the actuator.

3. In an engine starter having a pinion, an actuator, a screw threaded connection between the pinion and the actuator whereby relative rotation therebetween effects endwise movement of one with respect to the other to propel the pinion into and out of mesh with the ring gear of an engine to be started, and having a driving head: an impositive endwise resilient driving connection between the driving head and the actuator comprising a plurality of cupped spring washers confined under a degree of compression between the driving head and the actuator sufficient to establish an initial torque transmitting connection from the driving head to the adjacent washer and through the stack of washers to the actuator solely through frictional engagement; means engaging one peripheral edge of all of the washers for holding them axially aligned, the other peripheral edge of all of the washers being entirely free for radial movement in or out as endwise pressure on the stack of washers varies; and a pinion stop for limiting advance of the pinion so that the torque impositively transmitted to the actuator by the friction between adjacent spring washers is applied to the pinion.

4. In an engine starter having a pinion and a pinion actuator with a threaded connection therebetween so that relative rotation of said parts effects translation of the pinion toward and from its operative driving position: an impositive endwise resilient driving connection for the actuator comprising, a driving head adapted to be fixed to a power shaft to provide a fixed driving abutment, an abutment on the actuator, a plurality of cupped spring washers assembled alternately in a stack between said abutments on the actuator and driving head, means engaging one peripheral edge of all of the washers for holding them axially aligned, the other peripheral edge of the washers being entirely free to move radially in or out as endwise pressure on the stack varies, and means limiting separation of the actuator and driving head and holding the stack of cupped spring washers under a degree of endwise pressure so as to provide an endwise resilient slip coupling operable through friction between adjacent washers and between the end washers and said abutments to effect initial torque transmission from the driving head to the actuator; and a pinion stop for limiting advance of the pinion so that the torque impositively transmitted to the actuator by the friction between adjacent spring washers is applied to the pinion.
